UNITED STATES PATENT OFFICE.

GEORGE H. PEACOCK, OF WEBSTER, NEW YORK.

IMPROVEMENT IN COMBINATION LOCKS.

Specification forming part of Letters Patent No. 119,948, dated October 17, 1871.

To all whom it may concern:

Be it known that I, GEORGE H. PEACOCK, of Webster, in the county of Monroe and State of New York, have invented certain Improvements in Permutation Locks, of which the following is a specification:

My invention consists in the combination of the bolt, lever, and finger-bars in such a manner that the said bolt shall be thrown back by the proper manipulation of the said finger-bars. The object of my invention is to provide a readily-adjusted guard, which shall admit of being speedily opened by the operation of the fingers when knowing the order in which the finger-bars stand.

Figure 1 is a front view of the working parts, showing the bolt thrown up. Fig. 2 is a sectional view on the line *x x* of Fig. 1. Fig. 3 is a front view of the working parts, showing the bolt withdrawn. Fig. 4 is a sectional view on the line *y y* of Fig. 3. Fig. 5 is a side view of the lever and one of the finger-bars.

The self-locking bolt A is thrown up by the S-shaped spring B, and forced back by the pressure of the lower part of the cross-plate C against its (the bolt's) incline or sloping heel X, Fig. 2, said cross-plate constituting the perpendicular arm of a bent lever, having its fulcrum at the angle and its horizontal arm or arms D projecting above and across the tops of the finger-bars E E E and E'. The upward pressure of the finger-bar E' brings it against and tends to elevate the outer end of the said horizontal arm D, Fig. 3, thereby pressing the lower end of the said perpendicular arm or cross-plate C, Fig. 4, against the said sloping heel X, thus sliding back the said bolt A. Guards F F project from the lower part of the said cross-plate C at nearly right angles, and against the face of the said finger-bars E E E and E', thus preventing the movement of the lever, and, consequently, of the bolt A. Slots or gains G G are provided in the sides of each of the finger-bars E E E and E' at different elevations. When by the proper manipulation of the said finger-bars E E E and E' the slots or gains G, standing underneath the guards F F, are brought in a horizontal line in front of the said guards F F the bent lever, consisting of the said cross-plate C and arms D, may be moved by the upward pressure of the finger-bar E' against the outer end of one of the arms D, and, by elevat-

ing the same, produce a pressure of the lower part of the cross-plate C against the sloping heel X, thus sliding back the bolt A, Fig. 3. The finger-bars E E E and E' are each formed with their opposite sides or faces alike, thus making them reversible. There is also on each side of the said finger-bars E E E a shoulder, H, Fig. 5, which rests on the bearing I when the said finger-bars are not elevated, and which are brought up against the upper bearings J J when at their greatest height, at which time the tops of the finger-bars E E E are in contact with the ends of the arms D, but prevented from elevating the said arms by the shoulder H. The finger-bar E' has no shoulders; hence, when the finger-bars E E are put in proper position for the entrance of the guards F F into the slots or gains G, the said finger-bar E' may be raised to a greater height than the finger-bars E E E, Fig. 3, thus moving the lever and thereby sliding back the bolt A. By sinking the faces of the finger-bars E below the slot G, as at K, Fig. 5, the guard F will not press against the said sink or indenture K, but will allow the said finger-bars E to drop back, so that the shoulder above the said slot or gain G will lodge on the end of the guard F, leaving the slot G to be entered by the guard F. Numbers 1 2 3 4 5 6 7 8 are placed on the faces of the finger-bars E E E and E' to indicate their required movement. Figures 1 2 3 4, Fig. 1, are placed on the lower part of the cross-plate C to indicate the proper numbers on the finger-bars. The opposite faces of the finger-bars E E E and E' are numbered alike; hence any number on them may be made to stand under any number on the cross-plate.

I claim as my invention—

1. The bolt A having the incline X, and the lever consisting of the cross-plate C and arms D, in combination with the finger-bars E E E and E', substantially as and for the purpose set forth.

2. The bolt A having the incline X, spring B, cross-plate C, arms D, and guards F, in combination with the finger-bars E E E and E' provided with slots G G, shoulders H H, and indentures K, substantially as and for the purposes set forth.

GEORGE H. PEACOCK.
